PILL DISPENSING CONTAINER

Huna L. Apfelbaum, Brooklyn, N. Y., assignor to
 Victor Metal Products Corporation, Brooklyn,
 N. Y., a corporation of New York

Application November 9, 1942, Serial No. 465,015

2 Claims. (Cl. 206—42)

This invention relates to containers or vials for holding and dispensing pills, tablets and the like.

The invention contemplates the provision of a generally elongated container, such as a vial or pill box, having an axially slideable cap or cover provided with a side discharge opening which may be brought manually into registration with a corresponding side opening in the container part to permit the discharge of a single pill at a time, the cap normally closing the opening and preventing entrance of contaminating matter into the container.

The invention further contemplates the provision of a dispensing pill container adapted to be held in one hand of the user and readily operated by a finger of said hand, the entire container being made preferably of but two parts each adapted to be readily and economically molded of suitable plastic material.

The invention further contemplates the provision of simple and efficient means for slidably holding the cap part to the container part and for limiting the relative movement thereof, which means also permits the ready assembly of the two parts after the container has been filled with the pills to be dispensed.

The various objects of the invention will be clear from the description which follows and from the drawing, in which,

Fig. 1 is a perspective view of the container in its open or pill-discharging position, showing a pill dropping out therefrom.

Fig. 2 is a fragmentary combined rear view and vertical section of the container in the normal or closed position thereof.

Fig. 3 is a horizontal section of the same taken on the line 3—3 of Fig. 2.

Fig. 4 is an enlarged fragmentary combined side view and vertical section taken on the line 4—4 of Fig. 3.

Fig. 5 is a fragmentary front view of the upper portion of the container part showing the reduced extension of the guide slot.

In the practical embodiment of the invention shown by way of example, both the cap 10 and the container part 11 are preferably, though not necessarily molded of suitable plastic material, it being understood however, that other suitable material such as metal, paper or the like in sheet or tubular form may be used instead if desired and if available.

The container part 11 is closed at its lower end and open at its upper end edge 12, the cap 10 being slidably fitted into said open end to telescope with slight frictional resistance into and out of

the container part. Extending downwardly from the edge 12 and through the wall of the container part is the discharge opening 13, preferably rounded at its bottom edge. Spaced circumferentially at about 90° from the opening is the guide slot 14 which is parallel to the axes of the cap and the container part. As shown best in Fig. 5, the slot 14 has spaced parallel edges 15, 16 terminating at their upper ends at a point 10 slightly below the top edge 12. Extending downwardly from said top edge and into the slot 14 is the reduced slot portion 17, narrower at its bottom part than the slot 14 and preferably widened at the upper edge to provide a downwardly converging taper. A pair of spaced shoulders 18, 19 are thereby formed at the top of the slot 14 to engage the finger piece 20 projecting from the cap through the slot 14, said shoulders limiting the upward movement of said finger piece 20 in the slot.

The finger piece is preferably molded integrally with the cap and engages the bottom of the slot 14 when the cap is in its normal position shown in Fig. 2. In this position, the top surface 21 of the cap is preferably, though not necessarily coplanar or flush with the edge 12. It will be noted that the preferably cylindrical wall of the container part is comparatively thin and therefore slightly flexible. I utilize the flexibility of the wall to assemble the parts. Such flexibility of the upper part of the wall is increased by the freeing of that portion of the wall between the opening 13 and the slots 14, 17, from the remainder of the wall, by means of said opening and slots. Consequently, the thus freed wall parts yield enough to permit the finger piece to be forced downwardly through the normally narrower slot 17 into the wider slot 14, the sides of the slot spreading apart under the longitudinal pressure of the finger piece by reason of their taper resulting in a cam action, said slot sides springing together after the release of the spreading pressure thereon to confine the finger piece in the slot 14 and to hold the cap in place against separation from the container part.

It will be understood that prior to the assembly of the cap to the container part as above described, said part is filled with the pills to be dispensed or other contents. The top of the cap is closed by the wall 22, but the bottom is open and communicates with the interior of the container part, the depending wall 23 of the cap preferably being long enough to cover the slot 14 and to extend past the bottom of the dis-

charge opening 13 when the cap is collapsed or telescoped into the container part and the finger piece is at the bottom of the slot 14 (Fig. 2). The wall 22 normally therefore, not only excludes foreign matter from the interior of the container part, but also provides an adequate bearing on the inner surface of the container part to prevent any material rocking action of the cap during its opening movement on upward force exerted on the finger piece.

To expose the discharge opening 13 when the cap is partly projected or extended beyond the container part, said cap is formed with the opening 24 in the wall 23 in axial alignment with the opening 13, and extending upwardly from the bottom edge of said wall a distance substantially the same as the height of the opening 13. By reason of the opening 24 the resiliency of the lower edge portion of the cap is increased so that by squeezing inwardly the edges of the opening 24 to contract the edge part of the cap, the finger piece may be forced upwardly out of the slot. This may be done if it becomes desirable to refill the container part.

While both openings may be of any suitable shape, I prefer to round the upper edge of the opening 24 and the lower edge of the opening 13. The cap and container part may also have any desired cross-sectional shape, circular, polygonal or otherwise, since they merely slide relatively and do not rotate.

The container is easily held in one hand of the user and operated by the thumb or a finger of that hand to open it. On tilting the container to the position of Fig. 1, the pills drop down to the then registering openings 13 and 24 and a pill drops therethrough out of the container, after which the container is righted and the cap closed or collapsed by pushing it in or by operating the finger piece as may be found convenient.

It will be understood that various changes may be made from the structure shown and described without departing from the spirit of the invention or from the scope of the appended claims.

I claim:

1. A two piece dispensing container of the pocket type formed of non-metallic and substantially rigid plastic material comprising a first elongated tubular container part having a wall of the same cross sectional size and shape throughout its length, one end of said part being closed and the other end being open, said wall having a longitudinal slot therein extending from the end edge surrounding the open end toward the closed end, the slot having a constricted portion slightly below and adjacent said end edge, said wall also having an opening therein extending downwardly from said end edge a distance less than the length of the slot, the opening being in circumferentially spaced relation to the slot and cooperating with said slot to reduce the rigidity of the end edge portion of the wall thereby to permit the finger piece hereinafter mentioned to be forced downwardly through the constricted portion of the slot and into the lower portion of the slot, the wall between the slot and the opening yielding sufficiently for that purpose, and an elongated tubular cap part having a wall of the same cross sectional size and shape throughout its length, one end of the cap part being closed, the other end being open, the cap part being longitudinally slidable in the container part manually and being inserted thereinto with the closed end of the cap part exposed and the open end down, said cap part having a finger piece projecting therefrom and passing through the slot and slidable therein, said finger piece constituting the sole cap moving member, said cap part having an opening in the wall thereof extending from the open end upwardly and arranged in registration with the opening of the container part when the finger piece is at the top of the slot, the outer end surface of the cap part being normally coplanar with the end edge of the container part, the finger piece being normally arranged at the bottom of the slot, and the cap part being otherwise normally entirely concealed within the container part.

2. A two piece dispensing container of the pocket type formed of substantially rigid plastic material comprising an elongated tubular container part having a wall of substantially the same cross sectional size and shape throughout its length, one end of said part being closed and the other end being open, said wall having a longitudinal slot therein extending from the end edge surrounding the open end toward the closed end, the slot having a constricted portion adjacent said end edge, said wall also having an opening therein extending downwardly from said end edge, the opening being in circumferentially spaced relation to the slot and cooperating with said slot to reduce the rigidity of the end edge portion of the wall thereby to permit the finger piece hereinafter mentioned to be forced downwardly through the constricted portion of the slot and into the lower portion of the slot, the wall between the slot and the opening yielding sufficiently for that purpose, and an elongated tubular cap part having a wall of the same cross sectional size and shape throughout its length, one end of the cap part being closed, the other end being open, the cap part being longitudinally slidable in the container part manually and being inserted thereinto with the closed end of the cap part exposed and the open end down, said cap part having a finger piece projecting therefrom and passing through the slot and slidable therein, said finger piece constituting the sole cap moving member, said cap part having an opening in the wall thereof extending from the open end upwardly and arranged in registration with the opening of the container part when the finger piece is at the top of the slot, the outer end surface of the cap part being normally coplanar with the end edge of the container part, the finger piece being normally arranged at the bottom of the slot, and the cap part being otherwise entirely concealed within the container part.

3. A two piece dispensing container of the pocket type formed of substantially rigid plastic material comprising an elongated tubular container part having a wall of substantially the same cross sectional size and shape throughout its length, one end of said part being closed and the other end being open, said wall having a longitudinal slot therein extending from the end edge surrounding the open end toward the closed end, the slot having a constricted portion adjacent said end edge, said wall also having an opening therein extending downwardly from said end edge, the opening being in circumferentially spaced relation to the slot and cooperating with said slot to reduce the rigidity of the end edge portion of the wall thereby to permit the finger piece hereinafter mentioned to be forced downwardly through the constricted portion of the slot and into the lower portion of the slot, the wall between the slot and the opening yielding sufficiently for that purpose, and an elongated tubular cap part having a wall of the same cross sectional size and shape throughout its length, one end of the cap part being closed, the other end being open, the cap part being longitudinally slidable in the container part manually and being inserted thereinto with the closed end of the cap part exposed and the open end down, said cap part having a finger piece projecting therefrom and passing through the slot and slidable therein, said finger piece constituting the sole cap moving member, said cap part having an opening in the wall thereof extending from the open end upwardly and arranged in registration with the opening of the container part when the finger piece is at the top of the slot, the outer end surface of the cap part being normally coplanar with the end edge of the container part, the finger piece being normally arranged at the bottom of the slot, and the cap part being otherwise normally entirely concealed within the container part.

HUNA L. APFELBAUM.
